UNITED STATES PATENT OFFICE.

ALFRED HOFMANN, OF DUISBURG, GERMANY, ASSIGNOR TO THE BABCOCK & WILCOX COMPANY, OF BAYONNE, NEW JERSEY, A CORPORATION OF NEW JERSEY.

FLUID-HEATER CONTROL.

Application filed September 19, 1922. Serial No. 589,275.

To all whom it may concern:

Be it known that I, ALFRED HOFMANN, a citizen of Czechoslovakia, residing at Duisburg, Germany, have invented certain new and useful Improvements in Fluid-Heater Controls, of which the following is a specification.

The object of my invention is the provision of simple and effective means for controlling the temperature of a fluid heater.

My present invention will best be understood from the following description and the annexed drawing in which Figure 1 is a vertical, longitudinal section of a steam boiler economizer with its setting which I have chosen for the purpose of illustrating my invention, and Fig. 2 is a sectional view through the thermometer and the associated parts.

In the drawing, a flue 10 has connected to it an inlet flue 11 and an outlet flue 12. Connecting the inlet flue 11 and the outlet flue 12 is a by-pass flue 13. In the flue 10 is an economizer of a well known type, having a plurality of sections 14, 27 and 28 of vertical tubes connected at the top and bottom by headers, the sections being connected to each other by pipes 29 and 30, the inlet of the economizer 15 providing an entrance 30 for the cold water at the bottom of the first section and the outlet 16 providing an exit for the heated water at the top of the last section. The gases flow through the flues in the direction indicated by the arrows, and it will be seen that the general course of the water is counter to that of the flow of the gases; that is, the water enters at 15 and flows up through the tubes of the section 14, thence down through pipe 29 to the bottom of section 27 and again down through pipe 30 to the bottom of section 28, leaving at the outlet 16.

In this form of economizer, any steam formed in the last and hottest section 28 will pass up to the top headers and will pass off readily through the outlet 16 without seriously interfering with the operation of the economizer. If steaming occurs in any section except the last, however, such steam would have to be carried downward through pipes 29 and 30 and this might interfere seriously with the operation. Hence, I have provided an arrangement by which the passage of the hot gases over the economizer may be controlled automatical-

ly, preferably in accordance with the temperature of the water in the next to the last or hottest section.

Dampers 17 are provided at the entrance of the by-pass flue 13, these dampers being shown as double in form and interconnected, and operated in a manner to be described more fully hereinafter.

A thermometer 18 is provided at a point somewhere near the outlet 16 of the economizer, and preferably at the top of the next to the hottest section, the thermometer being arranged so that it is affected by the temperature of the water flowing through the economizer. The thermometer shown is of the expansible-fluid type, and the mercury usually used in such a thermometer is caused to move a contact member, so that, at a predetermined temperature, a circuit is closed through the wires 19 and 20 and a motor 21, which is connected by gearing 22 with one of the dampers 17, this latter damper being, in turn, connected through a link 23 with the other half of the damper.

If desired, additional dampers 24 and 25 may be provided at the entrance and exit, respectively, of the flue 10. Also, if desired, a signaling device such as a lamp 26, may be provided to be operated at the time that the circuit through 19 and 20 is closed.

In practice, the dampers 17 will be closed normally, so that all of the hot gases from the flue 11 will pass across the economizer tubes and out of the outlet 12. If, however, because of changes in the boiler operating conditions, the temperature of the gases rises unduly, or if, for any reason, the flow of water through the economizer is cut down, it will then become desirable to prevent an undue rise of pressure in the economizer, and my invention will accomplish this. By locating the thermometer 18 at a point somewhere near the outlet, it will be evident that if, because of operating conditions, the temperature of the water rises to a predetermined point, the electric circuits through the motor 21 will be closed and the dampers 17 opened, to shunt or bypass some of the gases around the economizer.

By locating the thermometer in the next to the hottest section, the temperature at which the dampers operate to shunt the gases may be such as to insure that no steaming will take place in any section ex-

cept the last, and yet maintain the water leaving the economizer at a temperature which may cause steaming.

By the use of a signaling device, such as the lamp 26, the attention of the operator may be called to the operating conditions when the automatic device operates. If desired, the automatic feature may be dispensed with, and the operator will then move the appropriate dampers by hand when the signal indicates the changed operating conditions.

Instead of moving the damper 17 to full open or closed position at each operation, provision may be made to cause the damper to be only partially opened or closed at each operation, so that each successive rise or fall of the temperature will cause a partial opening or closing of the damper; that is to say, the damper will be moved by successive steps.

I claim:—

1. In combination, a flue for hot gases, a fluid heater in the flue, said heater having an inlet and an outlet whereby fluid may flow therethrough while being heated, a thermometer in the fluid near the outlet, an electric circuit including a signal, and arranged to be closed when the temperature indicated by the thermometer reaches a predetermined point.

2. In combination, a flue for hot gases, a fluid heater divided into sections and located in said flue, inlet and outlet connections to the fluid heater and between the sections thereof to cause the water to flow successively through the sections in a general direction opposite to that of the hot gases through the flue, a by-pass for the hot gases around the fluid heater, and automatic means, controlled by the temperature of the fluid being heated in the next to the hottest section of the economizer, to regulate the flow of the gases through the by-pass.

3. In combination, a flue for hot gases, a

fluid heater divided into sections and located in said flue, inlet and outlet connections to the fluid heater and between the sections thereof to cause the water to flow successively through the sections in a general direction opposite to that of the hot gases through the flue, a by-pass for the hot gases around the fluid heater, a thermometer in the fluid near the outlet of the next to the last section of the fluid heater, and automatic means, controlled by said thermometer, to regulate the flow of the gases through the by-pass.

4. In combination, a horizontal flue for hot gases, a fluid heater therein, having a plurality of sections comprising vertical tubes connected by headers, inlet and outlet connections to the fluid heater and between the upper and lower headers of adjacent sections arranged to cause the water to flow successively through the sections in a general direction opposite to that of the hot gases through the flue, a by-pass for the hot gases around the fluid heater, and automatic means, controlled by the temperature of the fluid being heated in the next to the hottest section of the economizer, to regulate the flow of the gases through the by-pass.

5. In combination, a horizontal flue for hot gases, a fluid heater therein, having a plurality of sections comprising vertical tubes connected by headers, inlet and outlet connections to the fluid heater and between the upper and lower headers of adjacent sections arranged to cause the water to flow successively through the sections in a general direction opposite to that of the hot gases through the flue, a by-pass for the hot gases around the fluid heater, a thermometer in the fluid near the outlet of the next to the last section of the fluid heater, and automatic means, controlled by said thermometer, to regulate the flow of the gases through the by-pass.

ALFRED HOFMANN.
